CLAIM

The ornamental design for a panel for air conditioner, as shown and described.

DESCRIPTION

FIG. 1 is a perspective view of a panel for air conditioner showing my new design;

FIG. 2 is a front view thereof;

FIG. 3 is a rear view thereof;

FIG. 4 is a top view thereof, shown in a reduced scale;

FIG. 5 is a bottom view thereof, shown in a reduced scale;

FIG. 6 is a left side view thereof, shown in a reduced scale;

FIG. 7 is a right side view thereof, shown in a reduced scale; and,

FIG. 8 is a cross-sectional view thereof, shown in an enlarged scale, taken along the line 8-8 in FIG. 2; and,

FIG. 9 is a perspective view thereof with the louver shown in an opened condition.
